Henry Williams

INVENTOR.

UNITED STATES PATENT OFFICE.

JOSEPH W. EVANS, OF NEWBURYPORT, MASSACHUSETTS.

DRAW-GEAR FOR STREET-CARS.

SPECIFICATION forming part of Letters Patent No. 377,825, dated February 14, 1888.

Application filed November 9, 1887. Serial No. 254,679. (No model.)

To all whom it may concern:

Be it known that I, JOSEPH W. EVANS, of Newburyport, in the county of Essex and State of Massachusetts, have invented a new and useful Improvement in Street-Railway Cars, of which the following is a specification.

It is found in practice that by reason of the jar, jolting, or from other causes the draw-pins in street-cars are apt to jump out from or work up in the draw-irons or draw-bars. My present invention has for its object to remedy this difficulty.

In the accompanying drawings, in which similar letters of reference indicate like parts, Figure 1 is a perspective view showing the dasher-rail and adjacent portions of a street-car, and embodying my invention. Fig. 2 is a vertical section of my device with the draw-pin lowered into position and held therein. Fig. 3 is a similar section with the draw-pin raised. In Figs. 2 and 3 a portion of the lifting-rod is represented as having been broken out.

A represents the dasher; A', the dasher-rail, the upper portion being made usually of wood and the lower portion of metal; B, the draw-iron or draw-bar provided with the vertical perforations B' B'; and C, the pole provided with the perforation C', all constructed as usual. D is a metallic bracket of substantially the shape shown. A portion, D', extends rearward under the dasher-rail, and is bolted rigidly thereto, as at d, and the bracket is further provided with two arms, D'' D'', which extend forward horizontally and form bearings for the pivot d'. Loose on this pivot is the lever E, of which E' is the handle. This lever is provided with two parallel arms, E'', on its under side, which form bearings for the pivot e, from which depends the lifting-rod H, bent rearward, as shown at H', and to the lower

end of which is pivotally secured at h the draw-pin I.

When the device is in the position shown in Figs. 1 and 2, the draw-pin is in the perforations B' B' C, and as the pivot e is slightly back of the pivot d' the rod H cannot be raised by any vertical force exerted on it, and hence the draw-pin I cannot be jolted out of its position in the draw-bar. To raise the rod H and release the pole C from the draw-pin, lift the handle E' of the lever E and swing it over upon the dasher-rail, as shown in Fig. 3. By means of the bend in the rod H the lever E is enabled to swing over far enough upon the dasher-rail to remain in the position shown in Fig. 3 until it is desired to again drop the pin into the draw-bar.

Having thus fully described my invention, what I claim, and desire to secure by Letters Patent, is—

1. The combination, with the dasher-rail and draw-bar of a street-railway car, of a bracket rigidly secured to said dasher-rail, a lever pivotally secured to said bracket, and a lifting-rod pivotally suspended from said lever and sustaining the draw-pin, said parts being constructed and arranged to allow the point on the lever at which the lifting-rod is suspended to swing past the center when the rod is lowered, substantially as and for the purpose set forth.

2. The combination of the dasher-rail A', bracket D D' D'', pivot d', lever E E' E'', pivot e, lifting-rod H, bent at H', as described, draw-pin I, and draw-bar B, substantially as and for the purpose described.

JOSEPH W. EVANS.
